YARN PACKAGE SUPPORT

Thomas M. Hurst, Rock Hill, S. C., assignor to
Celanese Corporation of America, a corpora-
tion of Delaware

Application March 4, 1948, Serial No. 13,031

4 Claims. (Cl. 242—120)

1

This invention relates to yarn package supports and relates more particularly to a bobbin comprising a demountable assembly of interchangeable bobbin elements.

Bobbins commonly employed in the textile art generally consist of a central barrel and provided at one or both ends with a suitable flange integral with the barrel, depending upon the type of yarn package to be formed. The flange or flanges may be glued or nailed to the barrel or provided with screws for holding the flange and barrel in fixed relationship. In some instances the flange or flanges and the barrel may comprise an integral unit formed by molding or by turning operations and the like. The yarns are wound on to the barrel of the bobbin and the yarn package formed may then be employed for warping, coning, pirning, or other textile operations where the yarn is removed from the bobbin barrel and re-wound to form another type of yarn package. Bobbins of the type described are normally re-used a large number of times and are frequently subjected to rather rough handling. Such rough handling frequently injures the flanges and/or the barrel of the bobbin to such an extent that the bobbin can no longer be employed to form yarn packages which will be entirely satisfactory. Such damaged bobbins are usually discarded since the time involved in dis-assembling them for repair or replacement of parts makes such an operation entirely uneconomical. This is particularly true of bobbins in which the several elements are glued or nailed together. Where the damaged bobbin is molded or formed as a single, integral unit any repairs are out of the question.

It is, accordingly, an important object of this invention to provide a bobbin comprising a demountable assembly of interchangeable bobbin elements adapted to be dis-assembled easily and quickly whereby damaged elements of said assembly may be readily replaced.

Other objects of this invention, together with certain details of construction and arrangement of parts, will appear from the following detailed description and the accompanying drawing.

In the drawing wherein a preferred embodiment of my invention is shown:

Fig. 1 is an elevational view, partly broken away and partly in section, showing my novel bobbin in assembled form;

Fig. 2 is a sectional plan view of the bobbin taken along the line 2—2 in Fig. 1 in the direction of the arrows;

Fig. 3 is an elevational view, partly broken

2

away, of the element forming the barrel of said bobbin assembly;

Fig. 4 is a detail view of a retaining ring element employed in forming my novel bobbin assembly; and

Fig. 5 is a view in perspective of a flanged end element of my novel bobbin structure.

Like reference numerals indicate like parts throughout the several views of the drawing.

Referring now to the drawing, and more particularly, to Fig. 1, the bobbin assembly of my invention, generally indicated by reference numeral 5, comprises a barrel 6 provided with a base flange 7 having integral therewith a bushing 8, said flange and bushing having a hole 9 drilled therethrough which is adapted to receive the driven spindle (not shown) by means of which the bobbin is rotated when yarn is wound thereon. Flange 7 is recessed at 10 to receive the lower end of barrel 6. This structure prevents any of the yarn windings on said barrel 6 from being trapped between the inner surface of flange 7 and the barrel 6. The opposite end of barrel 6 is provided with a top flange 11 formed integral with a bushing 12 and a knob or handle 13. The latter provides the means by which the bobbin 5 may be gripped by an operative either to be placed in position on the spindle or doffed during winding operations. Flange 11 is recessed at 14 to receive the end of barrel 6 and to provide a tight-fitting joint which avoids the trapping of yarn during winding operations. Flange 11, bushing 12 and knob 13 are formed with a central cylindrical hole 15. The free-end surface of knob 13 is provided with an annular recess 16 adapted to receive some form of identification disc (not shown) adapted to carry any necessary information as to the nature of the yarn wound on barrel 6 of bobbin 5.

In order to hold bushing 12 in fixed relation to barrel 6, said bushing is provided with a circumferential groove 17 adapted to receive a flexible split retaining ring 18 formed of a suitable material such as spring steel, or the like. When the flange and barrel elements forming said bobbin are assembled retaining ring 18 is fitted on bushing 12, then compressed, and said elements fitted together and retaining ring 18 then permitted to expand into a circular groove 19 cut in the inner wall of barrel 6. Bushing 12 is vertically slotted at 20 so that the internally disposed lugs 21 of retaining ring 18 will be easily accessible after retaining ring 18 is circumferential groove 17 is expanded into slot 19. Lugs 21 are

provided with holes 22 for a purpose which will hereinafter be described in detail.

Bushing 8 which is integral with lower flange 7 is also held in fixed relation to the lower end of barrel 6 in a fashion similar to that described above in connection with bushing 12. Bushing 8 is provided with a circumferential groove 23 adapted to receive the retaining ring 18 which registers with and expands into a circular internal groove 24 when said elements are assembled. 10 Bushing 8 is provided with a vertical slot 25 so that the internally disposed lugs 21 of retaining ring 18 will clear the circumferential groove 23 and be easily accessible.

In order to remove flange 7 from barrel 6, for example, a suitable tool (not shown) is introduced through hole 9 and registered in the holes 22 provided in lugs 21 of the retaining ring 18. The tool is caused to draw lugs 22 together thus compressing the retaining ring 18 sufficiently to clear 20 groove 24. The bushing 8 and flange 7, integral therewith, may then be withdrawn and separated from barrel 6. Similarly, top flange 11 may be removed from barrel 6 by inserting said tool through hole 15, registering said tool in the holes 22, provided in lugs 21 of the retaining ring 18, compressing said retaining ring 18 by drawing lugs 21 together and then slipping barrel 6 off bushing 12 when the compressed retaining ring has cleared internal groove 19.

The dis-assembled flange and barrel elements may then be quickly reassembled after any damaged elements have been replaced by fitting retaining ring 18 on bushing 12, compressing the retaining ring 18 sufficiently to clear the internal diameter of barrel 6 and then telescoping the parts until retaining ring 18 snaps into internal groove 19 or 24, as the case may be, depending upon whether upper flange 11 or lower flange 7, is being replaced. Thus, one or more new flanges may be placed on barrel 6, or, if said barrel is damaged, the latter may be replaced and reassembled with the undamaged upper and lower flanges.

The flange and barrel elements of the novel bobbin of my invention may be formed of wood, metal, metal alloy, vulcanized fiber or of any suitable thermoplastic or thermosetting molding composition which is capable of yielding elements of sufficient lightness and strength to be employed satisfactorily in forming said bobbins. Where a headless package is to be formed, upper flange 11 may be replaced by a smooth, suitably shaped plug (not shown), the bushing of which may be inserted in barrel 6 and locked in position.

It is to be understood that the foregoing detailed description is given merely by way of illustration and that many variations may be made therein without departing from the spirit of my invention.

Having described my invention, what I desire to 60 secure by Letters Patent is:

1. A yarn package support comprising, in combination, a barrel having an internal groove therein and a flange at at least one end of said barrel, a bushing fixed to said flange and adapted to be received within said barrel, said bushing having a circumferential groove therein and a slot communicating with said groove, and a flexible retaining ring adapted to cooperate with said grooves, the construction and arrangement being such that the said retaining ring detachably secures the bushing and flange to said barrel.

2. A yarn package support comprising, in combination, a barrel having an internal groove therein and a flange at at least one end of said barrel, a bushing integral with said flange and adapted to be received within said barrel, said bushing having a circumferential groove therein and a slot extending vertically of said bushing and communicating with said groove, and a flexible retaining ring adapted to cooperate with said grooves, the construction and arrangement being such that the said retaining ring detachably secures the bushing and flange to said barrel.

3. A yarn package support comprising, in combination, a barrel having an internal groove therein and a flange at at least one end of said barrel, a bushing integral with said flange and adapted to be received within said barrel, said bushing having a circumferential groove therein and a slot extending vertically of said bushing and communicating with said groove, and a flexible, split retaining ring adapted to cooperate with said grooves, the construction and arrangement being such that the said retaining ring detachably secures the bushing and flange to said barrel.

4. A yarn package support comprising, in combination, a barrel and a flange at at least one end of said barrel, said flange being provided with an integral vertically slotted bushing adapted to be fitted within the barrel, and means comprising a circumferential groove in the periphery of said vertically slotted bushing, an internal groove in said barrel and a flexible retaining ring provided with perforated lugs registerable in said vertical bushing slot and adapted to cooperate with said grooves, whereby the bushing and flange are detachably secured to said barrel.
